UNITED STATES PATENT OFFICE.

AUGUST LEANDER NILSSON, OF SODERTALJE, SWEDEN.

CARBURETOR.

Application filed March 8, 1923, Serial No. 623,789, and in Sweden March 4, 1922.

On closely inspecting and testing the carburetors of internal combustion engines as heretofore used, it has been found that the proportions between fuel and air, when passing the motor from no-load running over to partial-load running and, further, to full-load running, have not been the most suitable, in spite of great care having been taken to bring about an adequate adjusting means 10 for the said purpose. This particularly holds good in respect of the carburetor types now mostly used, and which are provided with a Venturi tube and with a common throttling device in the air passage. These 15 carburetors truly consist of two such units built together, one being provided for no-load running and one for operation under load.

An arrangement whereby the amounts of 20 fuel will be accurately adjusted to all transitions, loads and speeds, has been brought about by virtue of the present invention.

The invention is principally distinguished by the main orifice of the carburetor being 25 divided in two or more nozzles situated in series behind each other, said orifices communicating partly with one another and partly with the no-load orifice of the carburetor in such manner that, on a sucking 30 action taking place through the first mentioned orifices, there will be produced a vacuum between them which, as far as may be required, is caused to impede the fuel delivered to the no-load orifice, and which 35 vacuum will thus be determinative of the amount of fuel delivered to the no-load orifice.

The amount of such fuel always corresponding to the load of the motor prevailing 40 for the time being may be simply brought about by suitably dimensioning the different main orifices relatively to each other.

The accompanying drawing illustrates an 45 embodiment of the invention. Fig. 1 is a vertical section of a carburetor devised in accordance with the invention, and Fig. 2 is a section on line 2—2 in Fig. 1. Fig. 3 discloses a modified embodiment.

50 The sections of the passages of the main orifices must always be so adjusted relatively to each other that they will in each case admit the requisite amount of fuel which always has to primarily pass through the main orifice situated first in the series,

and then through the other orifice or the other orifices.

According to the drawing, there are two main orifices 1 and 2 arranged in series in such manner that the fuel from the container 14 will first pass through orifice 1 and then through orifice 2, whereupon the fuel enters the space between the sleeves 9 and 15 whence it passes through the apertures 10 to the channel 16, from which the fuel is 60 discharged through the openings 17 into the air passage or Venturi tube 6. The main orifices 1 and 2 communicate through the connecting passage 3 with the no-load orifice 5. The amount of fuel discharged through 65 the latter passes through the channel 4 to the no-load outlet 7, or to the partial-load outlet 8, or to both.

The velocity of the fuel through the no-load orifice 5 is dependent on the fall of 70 pressure between the connecting passage 3 and the no-load channel 4. Therefore, by changing the vacuum in the connecting passage, the delivery of fuel to the no-load channel 4 and thus to the partial-load outlet 8 may be caused to decrease at a higher or lower rate, while the throttle device 18 is being opened. The amount of fuel from the partial-load outlet 8 may thus be adjusted to the delivery from the main outlet 85 17, so that the mixture will be the proper one also at times when both outlets are delivering simultaneously.

The arrangement of orifices as described hereinabove may be carried out so that the 90 main orifices 1 and 2 as well as the no-load orifice 5 are mounted in a special shell 9 adapted to be removed, and which is provided with outlet openings, partly 10 from the main orifice, and partly 11 from the no-load nozzle. Air is admitted from the well 95 20 through certain openings 12 and 13 in the said shell, such air effecting the first atomization of the fuel.

The device may be disposed either in a 100 lateral channel opening into the narrowest portion of the main passage, or, it may be mounted in the latter direct.

What I claim as new and desire to secure by Letters Patent of the United States of 105 America is:—

In a carburetor, in combination, a casing having an induction tube, an air duct leading to said induction tube and a well, means having a calibrated orifice at the bottom of 110

said well, a fuel supply duct leading to said orifice, a sleeve within said well forming a chamber at the bottom thereof for which the orifice is an inlet and having a restriction within its bore, said restriction admitting fuel from said chamber to said sleeve, a second sleeve around said first sleeve and spaced to provide a normal fuel passage be-

tween said sleeves, an outlet from said chamber to said normal fuel passage, ports in said second sleeve communicating with said air duct, a port leading from said air duct to said first sleeve, and a duct leading from said sleeve to said induction tube. 10

In testimony whereof I affix my signature.
AUGUST LEANDER NILSSON.
